J. M. GHORMLEY

RADIOCABINET

Filed Sept. 30, 1927

INVENTOR.

Joseph M. Ghormley,
BY John B. Brady
ATTORNEY.

UNITED STATES PATENT OFFICE.

JOSEPH M. GHORMLEY, OF TORONTO, ONTARIO, CANADA, ASSIGNOR TO BRANDES LABORATORIES, INC., OF NEWARK, NEW JERSEY, A CORPORATION OF NEW JERSEY.

DESIGN FOR A RADIOCABINET.

Application filed September 30, 1927, Serial No. 23,583, and in Canada October 13, 1927. Term of patent 14 years.

To all whom it may concern:

Be it known that I, JOSEPH M. GHORMLEY, a citizen of the United States of America, residing at Toronto, in the Province of Ontario and Dominion of Canada, have invented a new, original, and ornamental Design for Radiocabinet, of which the following is a specification, reference being had

to the accompanying drawing, forming part thereof.

The figure is a perspective view showing my design of radio cabinet.

I claim:

The ornamental design for a radiocabinet as shown.

JOSEPH M. GHORMLEY.
